FUSE

Theodore Birkenmaier, St. Louis, Mo., assignor to
 W. N. Matthews Corporation, St. Louis, Mo., a
 corporation of Missouri

Application December 24, 1937, Serial No. 181,535

8 Claims. (Cl. 200—114)

This invention relates to fuses, and with regard to certain more specific features, to expulsion fuses.

The invention is an improvement upon the 5 structure shown in my Patent No. 2,077,207 for Fuse, dated April 13, 1937.

Among the several objects of the invention may be noted the provision of a fuse such as shown in said patent wherein an inside, instead 10 of an outside tube slides downwardly to effect the operation; the provision of apparatus of the class described which permits the advantages of the construction shown in said patent to be used in connection with the so-called knife contacts, 15 as well as with the latch-type of contacts shown in said patent; the provision of apparatus of this class which is adapted to drop the fuse link after withdrawing the same from the expulsion tube; and the provision of apparatus of the class in 20 which a door shall remain in place more effectively. Other objects will be in part obvious and in part pointed out hereinafter.

The invention accordingly comprises the elements and combinations of elements, features of 25 construction, and arrangements of parts which will be exemplified in the structures hereinafter described, and the scope of the application of which will be indicated in the following claims.

In the accompanying drawings in which is 30 illustrated one of various possible embodiments of the invention—

Fig. 1 is a vertical section of a fuse box incorporating the invention;

Fig. 2 is a front elevation of Fig. 1;

Fig. 3 is a bottom plan view of Fig. 1;

Fig. 4 is a view similar to Fig. 1 showing an alternative relationship of parts after blowing of a fuse;

Fig. 5 is a fragmentary rear elevation of a 40 clamping mechanism; and,

Fig. 6 is a bottom view of the parts shown in Fig. 5.

Similar reference characters indicate corresponding parts throughout the several views of 45 the drawings.

In some instances, it is desirable that the structure disclosed in my Patent 2,077,207, be used in connection with so-called knife contacts; that is, with contacts in which the terminal-engag- 50 ing portions on the fuse are springingly held between sideward spring clips. The solution of the problem of the application of said structure to such contacts is, among other things, herein given.

55 Referring now more particularly to Fig. 1,

there is shown at numeral 1 a fuse box having an open bottom 2. The box includes a septum 3 notched at 83 for accommodating a tube 29 to be described. The box also has a pivot pin 3 for the hook-shaped portion 5 of a door 7, the latter carrying an eye 9 for manipulating the same to open and closed positions. In open position, the door may be entirely separated from the box by unhooking the hook from the pivot pin 3. In closed position, the pin 3 and the 10 hook are inseparable. The box 1 and the door 7 are composed of insulating material, such as porcelain and "Bakelite" respectively.

The door of the present box is improved over that shown in said patent by providing laterally extending lugs 11 which swing down into position below the extensions 13 of the box when the door is swung down (see Fig. 4). Thus, if while depending, a lineman's tool or the like strikes the door and tends to force it upwardly, 20 it cannot be pushed up high enough to unlatch. However, it may be unlatched when at or near the dotted-line position B as shown in Fig. 1. It cannot be unlatched when in the dotted line position A shown in Fig. 4. Neither can it be 25 unlatched in the solid-line position shown either in Figures 1 or 4.

On the door 7 is an upper support 15 and a lower support 17, these being respectively integrally associated with terminal engaging elements 19 and 21. These terminal engaging elements have flat sides for engagement with the flat sides of spring line terminals 23 and 25, the latter being held fastened to the box 1. These line terminals 23 and 25 have wire-receiving 35 clamping yokes 27 for the usual wire-holding purposes.

From the above it will be seen that the contact between the terminal engaging elements 19 and 21 and the line terminals 23 and 25 are of 40 the so-called knife-contact variety which ordinarily would substantially resist any vertical motion and which consequently would resist the easy sliding down of the outside tube such as 43 of Patent 2,077,207.

In order that I may use the sliding tube arrangement of said patent, the terminal engaging elements 19 and 21 are joined by means of an outer insulating tube 29 or its equivalent. The tube 29 is threaded into the upper terminal en- 50 gaging element 19 and is held to the lower en- gaging element 21 by means of a set screw or the like.

The upper terminal engaging element 19 in- 55 cludes an opening 31 through which may be in-

serted, first the flexible lower length 33 of a fuse link and then a fusible portion 35 and an upper flexible portion 37. The opening 31 will not admit the attached head 39. The head 39 is clamped by means of a cap 41.

The fuse link, which I will hereinafter designate in general by the letter F is positioned within an inner insulating tube 43. This tube at its upper end slidably fits into a socket 45 in the 10 terminal engaging element 19. The tube 43 passes downwardly through the outer tube 29 and extends a slight distance from the lower end thereof. At its lower end it is provided with a 15 sideward notch 47 throughout which laterally passes the lower end of the fuse link F.

An outside ring 49 fastened on the inner tube 43 is adapted to drop down and rest upon an inner ring 51 fastened to the inside of the fixed outer tube 29. Thus the inner tube has a limited 20 downward motion such as illustrated in Fig. 4. This tube is free of any contact with the line terminals 23 or 25, and consequently there is no friction therewith.

To hold the lower end of the fuse link F, there 25 is provided on the lower terminal engaging element 21 a rearward conducting clevis 53. Pivoted to this clevis 53 is a downwardly extending arm 55 of conducting material which passes through a bridge 57. The bridge constitutes a means for 30 limiting the outward swing of the link 55. A spring 65 forces the arm 55 against the bridge (Fig. 4).

The link 55 reaches downwardly to a point where it in turn is formed as a clevis 59 between 35 the fingers of which is pivoted a clamping lever 61. The lever 61 is normally forced by a spring 63 in a clockwise direction (Fig. 4). The clockwise movement is limited by the action of a pin 71 which extends from the link 61 and engages 40 the underside of finger 67 of said clevis 59.

In view of the above it will be clear that since 45 the lever 55 is limited in its clockwise motion by the bridge 57 (Fig. 4), and the lever 61 is limited in its clockwise motion on lever 55 that the two levers assume a free position such as shown in Fig. 4 when the fuse link is not applied thereto.

Provision is made for applying the fuse link at its lower end to said levers as follows:

The lower end of the lever 61 is formed with a 50 lateral finger 73 (Figures 5 and 6) over which the lower end of the fuse link is placed. The fuse link end is then passed beneath a lateral clamping portion 75 on lever 61 and over a seat portion 77 on the finger 67 of lever 55.

When the fuse is placed in the position shown 55 in Figures 1, 3, 5 and 6, it is pulled enough so that there is a tendency to move the lower lever 61 counter-clockwise (see Fig. 1). This causes 60 its clamp 75 to clamp the fuse link F against the seat 77. Further pull draws the lever 55 against spring 65. Hence, under the tension of spring 65, the levers 55 and 61, are maintained in clamping 65 positions as shown in Fig. 1. Hence there is effected automatic clamping of the lower end of 70 the fuse link in response to tension in the spring 65. The tendency is to tension the fuse link in the tube 43, the lower end being relatively flexible, or, in the case of a very heavy fuse link, at 75 least to hold the link in a position to prevent the descent of the inner tube 43.

When the fuse link melts at the fusible section 80 35, the tension in spring 65 is released so that the lever 55 is pushed clockwise to effect a withdrawal 85 of the fuse link. The expulsion action in the tube 43 aids the effect and ultimately the lower

end of the fuse link is projected downwardly. The fuse link which has descended from the inner tube 43 has no longer any action on the pin 73 to make the lever 61 effective as a clamp on the end of the fuse link. Thus the lever 61 swings 80 clockwise on the link 55 to open clamp 75, thus releasing the fuse link which drops away from the box.

Next, the inner tube 43 slides down until the ring 49 rests on ring 51, as shown in Fig. 4. The tube 43 extending from box 1 then functions as a telltale. The tube 43 acts as a telltale to show that the fuse is blown, even though no fuse link is hanging therefrom. Thus not only is the invention of my former Patent 2,077,207 made applicable to knife contact switch structures but at the same time, I effect the advantage of having the major parts of the fuse link drop from the apparatus after it is melted, thus avoiding short circuiting with adjacent wires. 15 20

To reload the device, it is only necessary to bring the door 7 into the position B and remove it. The fuse cartridge being thereon may then be handled as follows:

The cap 41 is removed and a fresh fuse link fed 25 through the openings thus presented. The cap 41 is then replaced to clamp the head 39. The tube 43 at this time is again pushed up into the position shown in Fig. 1, and the lower end of the link is brought out from the bottom of the tube through the notch 47. The lower end of the link is then positioned over the fingers 73 and in between the clamping or holding portions 75 and 77. The fuse link is pulled taut and the lever 55 is thrown to the position shown in Fig. 1. Then, 30 35 upon release of the lever, the spring 65 tensions the levers 55 and 61 as described.

It will be understood that although the door 7 is shown as being hinged to the box 1, that it may be otherwise movably supported as by permitting the line terminals 23 and 25 to support the door assembly through the frictional engagement with the terminal engaging elements 19 and 21. 40

In view of the above, it will be seen that the 45 several objects of the invention are achieved and other advantageous results attained.

As many changes could be made in carrying out the above constructions without departing from the scope of the invention, it is intended 50 that all matter contained in the above description or shown in the accompanying drawings shall be interpreted as illustrative and not in a limiting sense. 55

I claim:

1. In apparatus of the class described, a base, spaced line terminals thereon, a movable member associated with the base, terminal engaging elements on the movable member cooperable with said line terminals, a fuse tube, means for slidably arranging said tube with respect to said terminal engaging elements, the tube being free of any engagement with the line terminals, a fuse link joining said terminal engaging elements and passing through said slidable tube, and means auxiliary to the tube for tensioning said fuse link prior to blowing and to aid in withdrawing the lower portion after the link has blown. 60 65

2. In apparatus of the class described, a base, spaced line terminals thereon, a movable member associated with the base, terminal engaging elements on the movable member cooperable with said line terminals, a fuse tube, means for slidably arranging said tube with respect to said terminal engaging elements, the tube being free of any en- 70 75 80 85 90

- gagement with the line terminals, a fuse link joining said terminal engaging elements and passing through said slideable tube, and means auxiliary to the tube for tensioning said fuse link prior to blowing to aid in withdrawing the lower portion after the link has blown, said slideable tube being supported by the fuse link while the latter is tensioned. 5
3. In apparatus of the class described, a base, spaced line terminals thereon, a hinged member on the base, terminal engaging elements on the hinged member cooperable with said line terminals, a fuse tube, means for slidably arranging said tube with respect to said terminal engaging elements, the tube being free of any engagement with the line terminals, a fuse link joining said terminal engaging elements and passing through said slideable tube, means auxiliary to the tube for tensioning said fuse link prior to blowing to aid 10 in its withdrawing the lower portion after the link has blown, said tensioning means being adapted to drop the withdrawn portion of link after withdrawal from said tube. 15
4. In apparatus of the class described, a base, spaced line terminals thereon, a hinged member on the base, terminal engaging elements on the hinged member cooperable with said line terminals, a fuse tube, an outer stationary tubular member rigidly joining said terminal engaging elements, a slideable expulsion tube within said outer tube, a fuse link joining said terminal engaging elements and passing through said expulsion tube and out of the lower end thereof, said fuse when in conducted position supporting 20 said expulsion tube and releasing said expulsion tube when the fuse blows, means for limiting the descent of the expulsion tube with respect to said stationary tube and means auxiliary to the tube for tensioning said fuse link prior to blowing for withdrawal of the same upon blowing. 25
5. In apparatus of the class described, a base, spaced line terminals thereon, a hinged member on the base, terminal engaging elements on the hinged member cooperable with said line terminals, an outer member rigidly joining said terminal engaging elements, a slideable expulsion tube within said outer member, a fuse link joining said terminal engaging elements and passing through said expulsion tube and out of the lower end thereof, said fuse when in conducted position supporting said expulsion tube and releasing said 30 expulsion tube when the fuse blows, means for limiting the descent of the expulsion tube with respect to said stationary tube and means auxiliary to the tube for tensioning said fuse link prior to blowing for withdrawal of the same upon blowing. 35
- for limiting the descent of the expulsion tube with respect to said stationary member, means auxiliary to the tube for tensioning said fuse link prior to blowing for withdrawal of the same upon blowing, said tensioning means being adapted subsequently to drop the withdrawn portion of the link to completely separate it from the apparatus. 5
6. In apparatus of the class described, a box, a door hinged to said box at the lower end, said box having an opening in the bottom, line terminals of the knife-contact variety in the box, terminal engaging elements on the door for engaging said line terminals, a movable tube located between said terminal engaging elements and having an open bottom, a fuse link joining said terminal engaging elements and passing through said movable tube and means auxiliary to the tube for tensioning said link prior to blowing to aid in withdrawing it as the fuse link blows, said movable tube being adapted to descend upon withdrawal of the link. 10
7. In apparatus of the class described, a box, a door hinged to said box at the lower end, said box having an opening in the bottom, line terminals of the knife-contact variety in the box, 15 terminal engaging elements on the door for engaging said line terminals, a movable tube having a bottom opening located between said terminal engaging elements, a fuse link joining said terminal engaging elements and passing through said movable tube and passing out of its lower end, means for tensioning said link to aid in withdrawing it when the fuse link blows, said movable tube being adapted to descend upon withdrawal of the link and means for limiting 20 the descent of the tube. 25
8. In apparatus of the class described, a box, a door hinged to said box at the lower end, said box having an opening in the bottom, line terminals of the knife-contact variety in the box, terminal 30 engaging elements on the door for engaging said line terminals, a sliding tube located between said terminal engaging elements, a fuse link joining said terminal engaging elements and passing through said slideable tube, means auxiliary to the tube for tensioning said link to aid in withdrawing it when the fuse link blows, said sliding tube being adapted to descend upon withdrawal 35 of the link, said tensioning means being adapted to drop said link after withdrawal thereof and means for limiting the descent of the tube. 40
